Primary Examiner — T. Chase Nelson*Assistant Examiner* — Jonathan J Han(74) *Attorney, Agent, or Firm* — Kilpatrick Townsend & Stockton LLP(57) **CLAIM**

The ornamental design for a slider for a slide fastener, as shown and described.

DESCRIPTION

FIG. 1 is a perspective view of the front, bottom and right side of a slider for a slide fastener, showing our new design; FIG. 2 is a front view thereof;

FIG. 3 is a rear view thereof;

FIG. 4 is a right side view thereof, the left side view being a mirror image thereof;

FIG. 5 is a top plan view thereof; and,

FIG. 6 is a bottom view thereof.

The broken lines shown are included for the purpose of illustrating the unclaimed portions of a slider for a slide fastener and form no part of the claimed design.

1 Claim, 5 Drawing Sheets---
